UNITED STATES PATENT OFFICE.

FRIEDRICH PAUL GEORGI, OF NIEDERPFANNENSTIEL, NEAR AUE, GERMANY.

ARMOR-PLATE FOR TREASURIES, SAFES, AND THE LIKE.

1,052,718.

Specification of Letters Patent.

Patented Feb. 11, 1913.

Application filed December 27, 1911. Serial No. 668,076.

To all whom it may concern:

Be it known that I, FRIEDRICH PAUL GEORGI, hüttenmeister, a subject of the King of Saxony, and a resident of Niederpfannenstiel, near Aue, Erzgebirge, in the Kingdom of Saxony, Germany, have invented a new and useful Armor-Plate for Treasuries, Safes, and the Like, of which the following is a specification.

10 This invention relates to a new armor-plate for treasures, safes and the like, which renders futile all attempts to pierce it by means of autogenic hole-burners.

15 The accompanying drawing represents a perspective view of an armor plate embodying my invention.

Hitherto the treasures, safes, and the like were by means of armor-plates protected from entering by force, the armor-plates 20 being now-a-days provided with so hard a crust that it is not possible to pierce them by means of mechanically driven tools. As is well known, the protection afforded by such plates has, however, been rendered 25 illusory by the autogenic hole-burners, which in the last years have come into use. The capacity of these tremendous tools of 30 piercing iron and steel is based upon the fact, that the metal is by the heat of the burners brought up to its igniting temperature and is by burning with the supplied oxygen turned into melted black oxid of iron which flows off and thus contributed to the formation of a hole in the plate.

35 In order to enable a given supply of heat, such as is represented by the said autogenic hole-burners, to produce the ignition and thereby the spontaneous continuation of the oxidation of a metal, it is necessary, that 40 the firing-point be attained and maintained. This is effected the more easily, the lower the temperature of ignition of the metal is, the higher its own heat of combustion is, the more badly the heat generated on some 45 place of the metal can escape, and the lower the heat-conducting power of the metal is.

Extensive experiments made by myself 50 have resulted in the knowledge, that also against the action of the autogenic hole-burners there is a protection possible by selecting a suitable metal. According to these experiments an armor-plate of pure nickel has proved to be sufficiently capable

of offering resistance against the flame of the said hole-burner; as this flame is not able to melt a hole through the plate. The reason for this property of the nickel lies in that the firing-point necessary for the formation of the melting oxid is not attained.

To burn nickel is more difficult than to burn iron. This is borne out by the fact, that ferric nickel can be freed from its iron by means of the Bessemer process, since it is the iron alone which burns and thus escapes. Evidently, to put it in other terms, the nickel burns more slowly at the same temperature than the iron. This means, that a quick combustion, such as is necessary for the spontaneous combustion, requires a higher temperature, and consequently the firing-point of the nickel must be considerably higher than that of the iron. Furthermore it is to be taken into consideration, that the black oxid formed by 75 burning the iron is melted at the firing-point of the iron and as it flows off constantly fresh iron is exposed to the action of the oxygen in the flame of the autogenic hole-burner, while the nickel on the contrary by the combustion is turned into 80 protodox of nickel, which is much less fusible than nickel, so that thereby the metal is protected from further action of the oxygen, as the transmission of the ignition is 85 rendered more difficult.

The nickel can be employed effectively against the attacks of the autogenic hole-burner, and may if desired be combined with plates or a system of bars of "drill-proof" metal and thus produce a compound armor-plate, which combines the best qualities of the two kinds, so that of course its effect is increased. The "drillproof" metal may be case-hardened cast-iron or of any 90 other known material, which can not be pierced by means of mechanically driven tools.

Claim:

An armor-plate for treasures, safes and the like made of nickel.

FRIEDRICH PAUL GEORGI. [L. s.]
